LOADED WAVEGUIDES.

Leslie Baden Mullett, Bernard Guest Loach, and George Lawson Adams, Malvern, Worcester, England, assignors, by mesne assignments, to the United States of America as represented by the United States Atomic Energy Commission.

Application December 11, 1952, Serial No. 325,306

4 Claims. (Cl. 333—31)

This invention relates to loaded waveguides for the propagation of electromagnetic waves with slow phase velocities.

In the specification of copending patent application Serial No. 236,932, filed July 16, 1951, now Patent No. 2,770,781, there is disclosed a loading means for a waveguide comprising an elongated sheet having inductive faces and adapted to be placed in a central plane of a rectangular waveguide parallel to the wider sides (the major median plane), the waveguide being dimensioned so as to cut-off the simple H_{01} mode.

The present invention is concerned with extensions and applications of the above mentioned disclosure.

According to the present invention a rectangular waveguide dimensioned so as to cut-off the simple H_{01} mode at the operating frequency is capacitatively loaded. Such loading may consist, for example, of corrugations in one or both walls of the guide or of transverse slots in a centrally arranged sheet. To be capacitative the corrugations or slots require to have effective transverse dimensions above cut-off i. e. greater than the width of the waveguide. This may be achieved by making the corrugated portion of the guide physically wider than the guide or by making the corrugations of the same or less width than the guide and filling them with dielectric. Alternatively the corrugations may be ribbed. In the case of a slotted plate the slots may be made physically longer than the width of the guide by giving them a curved, inclined, or zig-zag configuration or by thickening the plate over a part or parts of its width as disclosed in the specification of the aforesaid copending application. It will be understood that the equivalent of a slotted plate may be achieved by means of a series of parallel wires.

Reference is directed to the accompanying drawing wherein:

Fig. 1 illustrates a waveguide loading arrangement utilizing a series of spaced loading members of rectangular cross section.

Fig. 2 illustrates a waveguide loading arrangement incorporating a series of spaced loading members of circular cross section.

Fig. 3 illustrates a waveguide loading arrangement wherein a series of apertured members load the waveguide.

A waveguide dimensioned to be above the H_{01} cutoff may be either inductively or capacitively loaded. To cut-off the H_{01} mode the waveguide must be dimensioned to have a width less than $\lambda/2$ at the operating frequency. Various ways are available for achieving capacitive loading in the waveguide and, consequently, reduce the phase velocity of the electromagnetic wave transmitted by the waveguide, as will be more clearly pointed out below.

The waveguide dimensioned to cut-off the H_{01} mode at the operating frequency may be provided with corrugations in one or both of the guide walls. The corrugations may comprise pockets extending outward of

2

the guide walls in the wide dimension walls spaced longitudinally along the guide and having the same width dimension as the width of wide dimension walls. Or the pockets may be of greater width than the wider dimension walls. In both cases the pockets may be filled with dielectric material. The dielectric acts to render each corrugation, in effect, a short length of waveguide which is above cut-off, that is dimensioned to have an effective electrical length of greater than $\lambda/2$ the wavelength at the operating frequency. It will be appreciated that the slots may be less than the width of the guide if the constant of the dielectric is high enough. Unlike the conventional corrugated waveguide practice the depth of the corrugation is greater than $\lambda/4$.

Another method of loading the waveguide corrugation is to provide ridges along the centres of the wider sides of the waveguides constituted by the corrugation. These ridges are part of the corrugated portion of the waveguide and extend along the depth dimension of the corrugation pocket.

The loading means, instead of forming corrugation pockets exterior to the waveguide walls, may comprise a series of conductive slats extending down part way from one of the wider walls of the waveguide in a transverse plane to the guide and perpendicular to the plane of the narrower guide walls. As in the externally corrugated loading means the pocket may be filled with dielectric to further load the guide, or the walls of the corrugated extension may have ribs or ridges to provide the loading effect.

The embodiment as shown in Fig. 3 may be originally taken to comprise a rectangular waveguide with a series of slats disposed centrally within the guide walls. Dielectric filling or ridges on the slats may be utilized to add to the loading, thereby increasing the loading effect of the slats as a result of the increase in effective electrical wavelength of the loading structure disposed between the waveguide walls. The depth of the slats (the dimension along the narrower wall of the waveguide) tends to zero as the loaded guide wavelength is reduced to a value much less than the air wavelength. Hence, if the depth of the slats tend to zero, they may be replaced by a slotted plate having capacitative slots. For example, if the slats mentioned above are reduced in depth at their ends to leave a circular enlargement, ring or annular portion around a hole in the slat, as shown in Fig. 3, the series of slats may then be regarded as slotted plates with a semi-circular ridge along the centre of each face, these ridges providing capacitative loading for the slots.

A practical embodiment of an S-band loaded waveguide of the form shown in Fig. 3 and suitable for proton acceleration is of the following dimensions:

Cross section of guide	cm	4.5 x 3.4
Depth of slats 4 (or thickness of plate)	in	.125
Spacing of slats 4 (or width of slots)	in	.125
Diameter of hole	in	.394
Diameter of ring	in	.625

Since the dimensions of a normal S-band rectangular waveguide are 7.2 cm. x 3.4, a waveguide constructed and dimensioned as above is below cut-off for the H_{01} mode and is capacitatively loaded when operating in the S-band. The loading is such that for one air wavelength of 11.7 cm. the guide wavelength is 2.25 cm. The phase velocity is negative, in accordance with the invention.

A means of rendering the slots in a plate capacitative, which is an alternative to providing ridges, is to make the slots physically longer than half a wavelength (in air) by, for example, inclining the slots in a transverse plane of the waveguide or shaping the slots as shown

in Figs. 1 and 2. Using the inclined slots the displacement along the waveguide of the opposite ends of each slot must be small compared with the loaded guide wavelength.

In Figs. 1 and 2 the length of the slots is made longer than the wide dimension of the guide by, in effect, longitudinally corrugating the plate. The slot may be made from a rectangular piece of metal stock, or a piece of circular metal stock as shown in Fig. 2. Instead, however, of actually slotting a plate a series of spaced parallel round wires 2 or 3 are used and the wires are corrugated (zig-zagged) in the transverse plane of the guide.

One practical construction based on Fig. 2 for operation in S-band was dimensioned as follows:

Cross section of guide _____ 4.5 cm. x 3.4 cm.
 Diameter of wires 3 _____ .080 in.
 Pitch of wires 3 _____ .16 in.
 Shape of corrugations _____ 4 T. P. I. Whitworth
 thread form.

As in the previous dimensioned example, the above example cuts off the H_{01} mode when operating in the S-band and is capacitatively loaded, giving a negative phase velocity. The loading is such that for an air wavelength of 10.4 cm. the guide wavelength is 2.1 cm. This example of the invention has particular application in connection with micro-wave oscillators.

We claim:

1. A rectangular waveguide having narrower and **30** wider pairs of walls, means to excite the waveguide at a

frequency below the cutoff frequency of the waveguide, an electrical conductor connected between the narrower pair of waveguide walls in the major median plane from directly opposite points on said walls, at least a portion of said conductor being displaced from the axis of the line connecting said directly opposite points, the electrical length of said conductor being greater than one-half wavelength at said frequency.

2. A rectangular waveguide as claimed in claim 1, wherein said conductor is a round wire and said displaced portion comprises a series of corrugations.

3. A rectangular waveguide as claimed in claim 1, wherein the conductor is of rectangular cross section, said displaced portion comprising a series of zig-zag corrugations.

4. A rectangular waveguide as claimed in claim 1, wherein said conductor has an annular portion perpendicular to and extending above and below the major median plane and supported on opposite sides by conductor arms extending and connected to said directly opposite points.
